DESIGN FOR A COAT

Samuel Zimmerman, New York, N. Y.

Application January 21, 1941, Serial No. 98,190

Term of patent 3½ years

To all whom it may concern:

Be it known that I, Samuel Zimmerman, a citizen of the United States of America, residing in New York city, county of New York, and State of New York, have invented a new, original, and ornamental Design for a Coat, of which the following is a specification, reference being had to the accompanying drawing, forming part thereof, wherein,

The characteristic feature of my design resides in the combination on the coat disclosed of the specific stitched tuckings below the rear waistline, in association with the split belt member as shown.

I claim:

The ornamental design for a coat, substantially as shown and described.

SAMUEL ZIMMERMAN.
